CLAIM

[**] Term: 14 Years

The ornamental design for a decorative glass panel, as shown and described.

DESCRIPTION

FIG. 1 is a front elevational view of a decorative glass panel showing my new design; and

FIG. 2 is an enlarged fragmentary cross-sectional view taken along line 2—2 of FIG. 1.

The glass panel is transparent, and the appearance of the rear is essentially the same as the appearance of the front.
